John S. Peckham & Merritt Peckham, Utica, N.Y.
Letters Patent (Design No 85) dated 3rd October 1846

The schedule referred to in these Letters Patent and making part of the same.

To all to whom these presents shall come:

Whereas it is known, that we, John S. and Merritt Peckham, of Utica, in the County of Oneida, and State of New York, have invented or produced a new design for a stove, and that the following is a full, clear and exact description of the same, reference being had to the accompanying drawing, making part of this specification, which represents a side and end plate, of the stove.

The pattern is of semi-gothic form ornamented with tracery and flowers, and is composed of the following parts. The side plates (a) project at the centre, and the line of the top of the plate at that point curves upward in the segment of a circle: near each end of this there is a tablet or compartment extending nearly from top to bottom but narrow which incloses a garland of flowers pendant; the centre projecting part is supported on each side by two mullions, which terminate below in foliated tracery that extend into the centre ornament of scroll work. Above this ornament there is a lancet shaped recess with mouldings and a round headed panel in the centre; the mullions on each side of this recess are prominent and terminate in pendants below; on each side of the above named recess are others in curved and with very flat gothic heads the ground work of these recesses is ornamented with tracery in imitation of window sash highly ornamented and extending over the whole; above is an ornamental scroll work tracery.

The end plates (b) are divided into three compartments by mullions similar to those first described on the sides, and terminating in scroll work above or below; in the outside compartments are pendant garlands of flowers as on the side plates; the centre compartment is plain.

We claim the combination of the gothic tracery, garlands, and niches arranged in the ornamental design above described and represented.
